HUMIDISTAT

Filed March 7, 1928

EDWARD A. PORTER,
BY

H. S. Woodward,
ATTORNEY.

UNITED STATES PATENT OFFICE

EDWARD A. PORTER, OF BRATTLEBORO, VERMONT

HUMIDISTAT

Application filed March 7, 1928. Serial No. 259,862.

The invention has for an object to effect improvements in humidistats especially suitable for use in devices such as shown in my application Ser. No. 130,337, filed August 19, 5 1926, and has for an object to provide an adjustable automatic device of a novel kind for controlling the action of a humidifier to the end that the moisture content of air within a given compartment may be maintained in 10 any desired practical proportion suitable to goods or merchandise. It is especially useful in cigar cases. An important object is to embody this invention in such manner that it can be made very small in size, and adapted 15 to be readily installed and maintained in ordinary cigar cases.

A very important object of the invention is to so embody an appliance of this character that it will be liable in a minimum degree to 20 derangement or impairment incident to normal use and may be depended upon to operate with great certainty. It is an important aim to so embody a humidistat that an electric switch may be operated directly from 25 the moisture-sensitive element of the device thereby contributing to simplicity. It is also a further aim to provide a novel construction in such a switch.

Additional objects, advantages and features of invention reside in the construction, arrangement and combination of parts, as will be understood from the following details and description, and from the drawings, wherein

25 Figure 1 is an elevational view of the device as embodied in a form adapted to be suspended in a show-case.

Figure 2 is a longitudinal sectional view of the device, the case being omitted.

40 Figure 3 is an end view from the right of Figure 1.

Figure 4 is a cross sectional view on the line 4—4 of Figure 2.

45 Figure 5 is a fragmentary view showing an adjustable seat or abutment for the ends of the bows.

There is illustrated a humidistat comprising a sheet metal case 10, in which the humidistat proper is mounted, the case comprising 50 a back wall, integral top, bottom and end

walls, the open side of the case being closed by a removable cover 11, which preferably comprises bronze wire cloth or other material to permit free circulation of air. The upper and lower walls of the case are also foraminous, if desired, to permit air movement. The case in the present instance is provided with eye-bolts and chains 12, whereby it may be readily hung in the upper part of a showcase, and an electrical lamp receptacle 13 is 55 mounted on the top wall open therethrough in such manner that the lamp may be inserted from the exterior of the case. Upon the left-hand end of the case, two binding posts 14 are mounted, insulated in a suitable manner 60 from the case.

The humidistat proper comprises a horizontal chord bar 15, serving as a tension-stress-sustaining member, this bar carrying at each end two seats 16—17 against which 65 there are fitted at respective sides of the bar 15 hygroscopic wood bars bent to form bows 18, fitted snugly under compression endwise between the seats 16 and 17 in such manner that in case of accretion of moisture in the wood it will be caused to expand and to become bowed further. The seats 17 at one end of the bar 15 are made removable for adjustment, or replacement of the parts by provision of a flat flange on each projected longitudinally of the device and bolted to the bar 15, which is projected between the flanges. These seats may be connected at the sides to form a unit which may be slipped on or off the end of the bar 15. The bar in the present instance is formed of a T-shaped metal channel member, this being welded to the fixed seat elements 16. Two plates 19 are also attached to the sides of the bar midway of its length, which serve as a pivot mounting for circuit closing levers, to be described. Each of the hygroscopic wood bows is provided with a clock spring plate 20 at the outer side, corresponding in length, held in caps on the ends of the bows and under projected portions of the seat members 16 and 17, so as to be held close against the bow. These springs tend to oppose the bending of the bows slightly, and serve to insure return of the hygroscopic bows to initial positions upon decrease of 70 75 80 85 90 95 100

their water content. Pivoted between the plates 19 adjacent the plate 20 there are respective levers 21, projecting longitudinally beyond one end of the bar 18. These levers have contact screws 22—23 engaged through insulated plates on the levers, the screws being of sufficient length to contact with each other and close a circuit. One of these screws is of considerable length and has a head 24 extended through a suitable large opening in the bottom wall of the case 10 for manipulation to adjust the contact. A wire spring 25 is secured to one side of the bar 15 having respective arms bearing upon the outer sides of the levers 21 pressing them toward each other to hold the screws 22—23 yieldingly in contact. A short distance from the pivotal axis of each lever there is mounted on the outer side of each hygroscopic bow a knob 26, adapted to bear against the inner side of the lever, so that the levers will be separated at the outer ends by outward movement of the bows. By suitable adjustment of the screw 23 the levers will clear the bearing knob 26 when the desired degree of humidity is attained in the case wherein the device is installed, and any decrease of humidity will allow the bows to come closer together allowing the levers to be drawn inward by the spring 25 and close the contact between the screws 22—23.

The manner of utilizing the contact between the screws to close or open the circuit to an electrically operated device for supplying humid air or moisture to the chamber in which the present device is installed may be readily understood. In the present instance, a wire is led from each of the mounting plates of the screws 22—23, these wires being connected to respective binding posts 14. As a further precaution, the lamp receptacle may have respective wires led therefrom, one of which is connected to one binding post, while the other is led to one terminal of an electrical source, the other terminal of which is connected to the opposite binding post.

It will be seen that an extremely simple device is embodied, which, in the presence of air drier than it is desired to have surrounding the device will close an electrical circuit which may be utilized to operate any appliance for supplying humid air or moisture in other form. Ready adjustability of this device to function without disturbing the connection between the operative parts is an important advantage. It will be appreciated that by screwing in upon the screw 23 the bars 18 will have to be bowed to a much greater extent in order to cause opening of a circuit, thereby insuring a higher degree of humidity. On the other hand, should it be desired to maintain a lower degree of humidity, the screw 23 is operated so as to draw it outwardly, this allowing the outer ends of the levers to approach more closely toward

each other and resulting in earlier engagement of the bearing knob against the levers by expansive action of the bows. The wood of the bows may be impregnated with a hygroscopic salt, if desired, to increase its sensitivity to moisture in the air.

It has been my practice to use wood in the bow with the grain running transversely of the bow, as wood usually tends to expand and contract transversely more than longitudinally by the influence of moisture. I have also used laminated wood in the bow.

It is also possible to provide for adjustment of the device by mounting a screw 27 in the seat 17' at one end of each bow, arranged to press upon the metal cap 28 on the end of the bow.

I claim:

1. A humidistat comprising a non-hygroscopic bar, a bow of hygroscopic material seated at its ends on the bar and relatively movable members operatively mounted and associated with the bow and bar.

2. A humidistat comprising a bar having seats longitudinally spaced, a bow having its ends set respectively against the seats, said bow comprising longitudinal members of hygroscopic materials arranged so that the bow will vary its length under variations of humidity.

3. The structure of claim 1 in which the bow consists of an outer retaining member of flexible metal slidable upon the hygroscopic material and connected at its ends to the bar.

4. In a humidistat, a hygroscopically responsive bow device comprising a bar, a bow proper of hygroscopic material connected at its ends only to the bar, the bar forming a chord therefor.

5. A humidistat consisting of two hygroscopic bows having the property of expanding and contracting as their moisture content increases or decreases, a common chord non-responsive to moisture comprising a metal plate having seats adjacent the ends receiving the ends of the bows under compression, a plate carried by the chord at each side and extended beside the bows, a lever pivoted between the plates outwardly of each bow, a bearing connection being formed between the bows and levers, the levers being extended and having respective electrical contacts aligned for coengagement, at least one being adjustable and yielding means to press the levers toward the bows.

6. The structure of claim 4 in which said seats comprise a detachable unit secured to the end of said plate.

7. A humidistat comprising a central metal chord element having substantially T-shaped ends, and respective hygroscopic bows at each side having their ends set against the projections on the chord element.

8. The structure of claim 7 in which side

plates are secured to the chord element extending beside the bows, and beyond, levers pivoted between the projecting parts of the plates and laid movable in a plane with the bows, and having parts distant from their pivots arranged to be engaged by the bows, yielding means to bear the levers toward the bows, and coacting electrical contact carried respectively by the levers.

9. The structure of claim 7, in which the bows are in a vertical plane, contact-carrying members above and below the bows for co-engagement thereby, yielding means tending to hold the contact-carrying members co-engaged by the bows, contacts carried respectively by the contact-carrying members arranged to contact when the bows are disengaged from the contact-carrying members.

10. The structure of claim 7 in which the bows are in a vertical plane, contact-carrying members freely movable in said plane, above and below the bows respectively, and located for coengagement by the respective adjacent bows under bending action of the bows, yielding means coacting between and tending to hold the contact-carrying members against the bows, contacts on the contact-carrying members arranged to coengage when the bows are collapsed and spaced from the contact-carrying members, and an insulating stop positioned to engage and support the upper one of the contact-carrying members during disengaged positions of the bows.

11. A humidistat comprising a bow of hygroscopic material, seats held against movement and in which the ends of the bow are seated, and transmitting members in operative relation with the bow intermediate of its ends.

12. A humidistat comprising a bow of hygroscopic material, seats held against movement and in which the ends of the bow are seated; the seats at one end of the bow being adjustable to exert end pressure on the ends of the bow, and transmitting members in operative relation with the bow intermediate of its ends.

13. A humidistat comprising a bow of hygroscopic material held against outward movement at its ends, outwardly movable transmitting members in operative relation with the bow intermediate of its ends, springs pressing the free ends of the transmitting members toward each other, contacts carried by said free ends.

14. A humidistat comprising a bow of hygroscopic material seated at its opposite ends against outward movement to cause its members to flex outwardly between their ends, and electric contact members in the outward paths of the middle portions of the two bow members.

In testimony whereof I affix my signature.
EDWARD A. PORTER.
